(57) **CLAIM**

The ornamental design for a straight edge lid pen, as shown and described.

DESCRIPTION

FIG. 1 is a side perspective view of a straight edge lid pen showing my new design.

FIG. 2 is an enlarged side perspective view of the casing thereof, shown by itself for convenience of illustration.

FIG. 3 is a side perspective view of the whole pen from the opposite side from that shown in FIG. 1.

FIG. 4 is another side perspective view thereof, shown in a partially pulled out condition.

FIG. 5 is a side perspective view of the pen thereof, shown without the casing for convenience of illustration.

FIG. 6 is a side perspective view of the casing thereof, shown without the pen for convenience of illustration.

FIG. 7 is an enlarged cross-sectional view of the pen without the casing, taken at the point 7—7 in FIG. 5. The broken lines showing internal parts in the drawing of FIG. 7 are shown for environmental purposes only and form no part of the claimed design; and,

FIG. 8 is a top plan view of the casing thereof, shown by itself for convenience of illustration.
